UNITED STATES PATENT OFFICE

133,005

DESIGN FOR A COLLAR

Julius Edelson, New York, N. Y.

Application June 8, 1942, Serial No. 107,150

Term of patent 3½ years

To all whom it may concern:

Be it known that I, Julius Edelson, a citizen of the United States, residing in New York city, in the county of New York and State of New York, have invented a new, original, and ornamental Design for a Collar, of which the following is a specification, reference being had to the accompanying drawing, forming part thereof.

Fig. 1 is a front view of a collar showing my new design, and

Fig. 2 is a rear view of the collar shown in Fig. 1, and

Fig. 3 is a side elevational view of the collar shown in Figure 1.

I claim:

The ornamental design for a collar, substantially as shown.

JULIUS EDELSON.
